CLAIM

The ornamental design for a single-sole shoe with blue outpatch sole and contrasting upper, as shown and described.

DESCRIPTION

FIG. 1 is a perspective view of an embodiment of our new design of a single-sole shoe with blue outpatch sole and contrasting upper, where the color portions are indicated using the USPTO convention of horizontal lines for blue, and where the portions of the upper and the midsole that contrast with the outpatch sole are indicated using a slanted line hatching pattern;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1; and,

FIG. 7 is a back view of the design of FIG. 1.

The broken lines illustrating the half moon patch, the groove, and the heel stripe in the above described Figures are for illustrative purposes only and form no part of the claimed design.
